US0D1040120S

(12) **United States Design Patent** (10) Patent No.: **US D1,040,120 S**
(45) Date of Patent: ** Aug. 27, 2024

(54) **VIDEO CONFERENCE TERMINAL**

(71) Applicant: **Shenzhen Oceanwing Smart Innovations Technology Co., Ltd.**, Shenzhen (CN)

(72) Inventors: **Sichao Chen**, Shenzhen (CN); **Kebi Ding**, Shenzhen (CN); **Hyungwoo Yoon**, Shenzhen (CN)

(73) Assignee: **Shenzhen Oceanwing Smart Innovations Technology Co., Ltd.**, Shenzhen (CN)

(**) Term: **15 Years**

(21) Appl. No.: **29/823,540**

(22) Filed: **Jan. 18, 2022**

(30) **Foreign Application Priority Data**

Jul. 19, 2021 (CN) 202130458254.9

(51) LOC (14) Cl. **14-03**

(52) U.S. Cl.

USPC **D14/125**

(58) **Field of Classification Search**

USPC D14/125, 126, 129, 130, 133, 144, 1, D14/141.3, 149, 159, 167, 172, 217, 221, D14/204, 209.1, 225, 226, 238.1, 240, D14/308, 348, 349, 356, 358, 432, 496, D14/511, 239; D13/103, 107, 108

(57) **CLAIM**

The ornamental design for a video conference terminal, as shown and described.

DESCRIPTION

FIG. 1 is a front, right, top perspective view of a video conference terminal showing our new design;

FIG. 2 is a rear, left, bottom perspective view thereof;

FIG. 3 is a rear, right, bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines depicting the remainder of the video conference terminal form no part of the claimed design.

1 Claim, 9 Drawing Sheets
